UNITED STATES PATENT OFFICE.

THORINDA V. PARKER, OF MINNEAPOLIS, MINNESOTA.

CROCHET-HOOK.

1,210,975.

Specification of Letters Patent. Patented Jan. 2, 1917.

Application filed June 29, 1916. Serial No. 106,616.

To all whom it may concern:

Be it known that I, THORINDA V. PARKER, a citizen of the United States, residing at Minneapolis, in the county of Hennepin and State of Minnesota, have invented certain new and useful Improvements in Crochet-Hooks; and I do hereby declare the following to be a full, clear, and exact description of the invention, such as will enable others skilled in the art to which it appertains to make and use the same.

My invention has for its object to provide a simple and efficient interchangeable crochet hook in which a multiplicity of crochet hooks proper of different size are operatively connected to a single or common handle or holder that serves as a casing therefor.

In the accompanying drawings, which illustrate the invention, like characters indicate like parts throughout the several views.

Referring to the drawings: Figure 1 is a perspective view showing the complete crochet hook; Fig. 2 is a plan view of the same with some parts broken away, and some parts sectioned; Fig. 3 is a vertical section taken on the line x^3-x^3 of Fig. 2; Fig. 4 is a perspective view of the handle closing slide; Fig. 5 is an enlarged transverse section on line of the needle pivots; and Fig. 6 is a section on the line x^6-x^6 of Fig. 2.

The device comprises a multiplicity of hook needles 7 which at their free ends are provided with crochet hooks of different size so that they are adapted for use in the various kinds of crochet work. At their other ends, the hook needles 7 are perforated and loosely pivoted on the transverse pin or rivet 8 extended through and fastened to the edges of a tapered sheet metal handle or case 9. This handle 9 is channel-shaped in cross section, and has inturned edges on one face.

The numeral 10 indicates a flat wedge plate case adapted to be slid into the handle 9 just below the inturned edges. When the wedge plate 10 is positioned it closes the normally open side of the handle or case 9. To prevent the wedge plate 10 from slipping from working position, a lock segment 11 is pivoted to the closed side of the said handle and is provided at its free edge with an inturned flange that is adapted to be turned over the outer end of the said wedge plate 10, as best shown in Figs. 2 and 3. This lock segment 11 will be quite firmly

held in its closed position by friction or otherwise.

The contracted end of the handle 9 has a U-shaped form of such size that but one hook needle 7 at a time can be turned outward into an operative position. Furthermore, the open side of the contracted end of the said handle, (see Fig. 6), is of such width that needle 7 can be forced therethrough only by springing and slightly separating the sides of the said contracted portion. The spring tension of this contracted end of the handle is preferably such that it will hold the outturned needle properly projected for use. However, this is not absolutely necessary because when the wedge plate 10 is inserted, it will positively hold the outturned hook needle properly projected, and here it is important to note that the pivot 8 is located a considerable distance from the contracted end of the said handle. When the one needle is turned outward, the other needles will be confined within the handle and, of course, when the device is not in use, all of the needles or crochet hooks proper can be turned within the handle, the latter then serving as an inclosing case therefor.

This device can be made at small cost and is not only convenient, but affords a complete set of crochet hooks of different sizes and which, because of their attachment to a common handle, are not easily lost.

What I claim is:

1. The combination with a hollow handle affording a casing and provided with a displaceable side plate, of a plurality of crochet hooks movably mounted within said handle and adapted to be projected therefrom, one at a time, the said displaceable side when in position, serving to hold the projected crochet hook in its projecting position, and a lock piece movably applied to said handle and normally holding said displaceable side in its closed position.

2. The combination with a tapered hollow handle having flanged edges and a co-operating removable wedge plate at one side, of a multiplicity of crochet hooks pivotally attached within said handle at a point quite distant from its contracted end, the contracted end of said handle permitting but one hook at a time to be turned outwardly to an operative position, and the said wedge plate when in position serving to hold the outturned hook projected, and the other

hooks within said handle, and a lock piece movably applied to said handle and normally holding said wedge plate in its working position.

- 5 3. The combination with a tapered hollow handle having flanged edges and a coöperating removable wedge plate at one side, of a multiplicity of crochet hooks pivotally attached within said handle at a point quite
10 distant from its contracted end, the contracted end of said handle permitting but one hook at a time to be turned outwardly to an operative position, the said wedge plate when in posi-

tion serving to hold the outturned hook projected, and the other hooks within said handle, and a lock segment pivoted to the large end of said handle and provided with a segmental inturned flange normally overlapping the large end of said wedge plate and holding the same in working position. 15 20

In testimony whereof I affix my signature in presence of two witnesses.

THORINDA V. PARKER.
